UNITED STATES PATENT OFFICE

HOWARD A. THOMPSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

ELECTRICAL APPARATUS

Original application filed July 6, 1928, Serial No. 290,789. Divided and this application filed December 10, 1929, Serial No. 413,098.

My invention relates to electrical apparatus, and is particularly adapted for, though in no way limited to, railway traffic controlling apparatus.

5 The present application is a division of my co-pending application, Serial No. 290,789, filed July 6, 1928, for electrical apparatus.

I will describe one form of apparatus embodying my invention, and will then point 10 out the novel features thereof in claims.

In the accompanying drawings, Figs. 1, 1^a and 1^b are diagrammatic views which, when placed end to end in the order named, show one form of apparatus embodying my 15 invention. Figs. 2 to 11, inclusive, are views showing the phase relations and polarities of the currents in windings of the relays shown in Figs. 1, 1^a and 1^b.

Referring first to Figs. 1, 1^a and 1^b, the 20 reference characters 30 and 30^a, designate the track rails of a stretch of railway track along which traffic normally moves in the directions indicated by the arrows. These rails are divided by insulated joints 2 into a plurality 25 of track sections A—B, B—C, C—D, D—E, E—F, F—M, M—P and P—Q.

Each track section is provided with two 30 track relays designated by the reference characters H and K with appropriate ex- 35 ponents, each of which relays comprises two windings 5 and 6. The windings 5 of the relays H and K for each section are connected directly across the track rails adjacent the entrance end of the section, and the windings 40 6 are constantly connected with the secondary of a transformer designated by the reference character L with an exponent corresponding to the location. The primary of each transformer L is connected with a suitable source 45 of alternating current which is not shown in the drawings. Interposed between the winding 6 of each relay H and the secondary of the associated transformer L is an asymmetric unit 34, a second asymmetric unit 35 being connected across the terminals of the 50 relay. In similar manner interposed between the winding 6 of each relay K and the secondary of the associated transformer L is an asymmetric unit 36; an asymmetric unit 37 being connected across the terminals of the

relay. It will be plain, therefore, that each winding 6 is supplied only with half-waves of one polarity, and the parts are so proportioned that current flows in one direction through winding 6 of each relay H and in 55 the same direction but of opposite phase through winding 6 of each relay K. It follows that full-wave alternating current in the track rails will energize relays H and K in opposite directions. The currents in windings 6 of relays H and K are illustrated in Figs. 2 and 3, respectively.

Each track section is also provided with two transformers designated by the reference characters V and T, respectively, with distinguishing exponents corresponding to the location. The transformers V and T operate to supply current to the track rails of the 60 associated section from the adjacent transformer L in a manner which is controlled by 70 the two relays H and K for the section next in advance and which will be described in detail hereinafter.

The two relays H and K for each track section may also be used to control traffic governing means of any desired type. As here 75 shown, these traffic governing means are in the form of wayside signals one located at the entrance end of each section and designated by the reference character S with an exponent corresponding to the location. Each signal comprises nine lamps designated by the reference characters 58 to 66, inclusive, and each arranged to display a distinctive 80 signal indication when energized.

As shown in the drawing, the section immediately to the right of the point Q is occupied by a train W. Relays H^Q and K^Q are therefore de-energized and lamp 58 of signal S^Q is lighted, the circuit for this lamp passing from the right-hand terminal of the secondary of transformer L^Q, over contact 45—45^b of relay H^Q, contact 55—55^b or relay K^Q, and lamp 58 of signal S^Q, back to the midpoint of the secondary of transformer L^Q. Under these conditions, also, a circuit is completed for the primary 27 of transformer T^Q which may be traced from the right-hand terminal of the secondary of transformer L^Q, through contact 51—51^b of relay K^Q, contact 100

- 43—43^b of relay H^Q, and primary 27 of transformer T^Q, back to the mid-point of the secondary of transformer L^Q. The secondary 26 of the transformer T^Q is now connected with the track rails over a circuit which may be traced from the right-hand terminal of this secondary, through impedance 28, contact 42—42^b of relay H^Q, contact 48—48^b of relay K^Q, and asymmetric unit 39 to rail 30 of section P—Q, and from rail 30^a of this section back to the left-hand terminal of secondary 26 of transformer T^Q. Under the conditions just described, alternating current of normal relative phase is supplied to the rails 15 of section P—Q but since asymmetric unit 39 is interposed in the secondary circuit of transformer T^Q only the positive half-waves of this current flow in the rails of section P—Q as shown in Fig. 4.
- 20 Referring now to the apparatus located at point P, the positive half-waves of alternating current of normal relative phase supplied to the rails of section P—Q energize relay K^P in the normal direction but this current 25 does not energize relay H^P because it flows during the intervals that winding 6 of relay H^P is de-energized, so that the latter relay allows its contacts to assume their middle positions. A circuit is therefore completed for 30 lamp 59 of signal S^P over contact 45—45^b of relay H^P and contact 55—55^a of relay K^P, so that lamp 59 of signal S^P is lighted. A circuit is now closed from the left-hand terminal of the secondary of transformer L^P 35 through contact 51—51^a of relay K^P, contact 43—43^b of relay H^P, and primary 27 of transformer T^P back to the mid-point of the secondary of transformer L^P. The secondary 26 of transformer T^P is now connected with 40 the rails of section M—P through impedance 28, contact 42—42^b of relay H^P, contact 48—48^a of relay K^P and asymmetric unit 38. The rails of section M—P are therefore supplied with only the negative half-waves of 45 alternating current of reverse relative phase. This current is shown diagrammatically in Fig. 5.
- 50 Relay H^M is de-energized but relay K^M is energized in the reverse direction by the current flowing in section M—P. A circuit is completed for lamp 60 of signal S^M, over contact 45—45^b of relay H^M, and contact 55—55^a of relay K^M so that this lamp is lighted. A primary circuit is now closed for 55 transformer T^M from the left-hand terminal of the secondary of transformer L^M, over contact 51—51^a of relay K^M, contact 43—43^b of relay H^M, and primary 27 of transformer T^M, back to mid-point of the secondary of transformer L^M. The secondary 26 of transformer T^M is connected with the rails of section F—M over a circuit including impedance 28, contact 42—42^b of relay H^M, contact 48—48^a of relay K^M, and asymmetric unit 39, so that the rails 60 of section F—M are now supplied with only

the positive half-waves of alternating current of reverse relative phase as shown in the diagram, Fig. 6.

At point F, therefore, relay H^F is energized in the normal direction, but relay K^F is de-energized. Under these conditions, a circuit is completed, to light lamp 61 of signal S^F over contact 45—45^a of relay H^F and contact 56—56^b of relay K^F. The primary circuit of transformer T^F is now completed from the left-hand terminal of the secondary of transformer L^F, over contact 52—52^b of relay K^F, contact 43—43^a of relay H^F, and primary 27 of transformer T^F, back to the mid-point of the secondary of transformer L^F. The secondary 26 of transformer T^F is connected with the rails of section E—F over contact 42—42^a of relay H^F and contact 50—50^b of relay K^F. It will be noted that neither of the asymmetric units 38 or 39 at 85 point F is included in the secondary circuit for transformer T^F, so that full-wave alternating current of reverse relative phase is supplied to the rails of section E—F as shown in Fig. 7.

Considering next the apparatus located at point E, the current now flowing in the rails of section E—F energizes relay H^E in the normal direction and energizes relay K^E in the reverse direction, so that a circuit is completed for lamp 62 of signal S^E over contact 45—45^a of relay H^E and contact 56—56^b of relay K^E. Furthermore, a primary circuit is closed for the primary 27 of transformer T^E from the left-hand terminal of the secondary of transformer L^E, over contact 52—52^b of relay K^E, contact 43—43^a of relay H^E, and primary 27 of transformer T^E to the mid-point of the secondary of transformer L^E. A circuit is also completed for the primary 33 of transformer V^E, which circuit may be traced from the right-hand terminal of the secondary of transformer L^E, through contact 53—53^a of relay K^E, contact 44—44^a of relay H^E, and primary 33 of transformer V^E, back to the mid-point of secondary L^E. The secondary 26 of transformer T^E is now connected with the rails of section D—E over contact 42—42^a of relay H^E, contact 50—50^b of relay K^E and asymmetric unit 39. The positive half-waves of alternating current of reverse relative phase are therefore supplied to the rails of section D—E. Furthermore, the secondary 32 of transformer V^E is connected through impedance 90, contact 41—41^a of relay H^E, contact 47—47^a of relay K^E, and asymmetric unit 69, with rails of section D—E. The positive half-waves of alternating current of normal relative phase are therefore also supplied to the rails of section D—E and the current in this section may be represented by the diagram, Fig. 8.

At point D, relays H^D and K^D are both energized in the normal direction, and a circuit is completed for a lamp 63 of signal S^D,

over contact 45-45^a of relay H^D and contact 56-56^a of relay K^D. The primary circuit for transformer T^D may be traced from the right-hand terminal of the secondary of transformer L^D, through contact 52-52^a of relay K^D, contact 43-43^a of relay H^D, and primary 27 of transformer T^D back to the mid-point of the secondary of transformer L^D. The secondary 26 of transformer T^D is now connected with the rails of section C-D through impedance 28, contact 42-42^a of relay H^D, contact 50-50^a of relay K^D, and asymmetric unit 38. The rails of section C-D are therefore supplied with the negative half-waves of alternating current of normal relative phase as indicated in Fig. 9.

The current thus supplied to the rails of section C-D energizes relay H^C in the reverse direction, but relay K^C is de-energized, and a circuit is completed for lamp 64 of signal S^C over contact 45-45^c of relay H^C and contact 57-57^c of relay K^C. Current now flows from the right-hand terminal of the secondary transformer L^C over contact 43-43^c of relay H^C, and primary 27 of transformer T^C to the mid-point of a secondary of transformer L^C. Current is also supplied to the primary of transformer V^C over a circuit which may be traced from the left-hand terminal of the secondary of transformer L^C, through contact 54-54^c of relay K^C, contact 44-44^c of relay H^C, and primary 33 of transformer V^C, back to the mid-point of transformer L^C. The secondary 26 of transformer T^C is now connected to the rails of section B-C over contact 42-42^c of relay H^C, contact 49-49^c of relay K^C, and asymmetric unit 38. Furthermore, the secondary 32 of transformer V^C is now connected with the rails of section B-C over contact 40-40^c of relay H^C, contact 46-46^c of relay H^C, and asymmetric unit 68. The rails of section B-C are therefore supplied with only the negative half-waves of alternating currents of both normal and reverse phases as indicated by Fig. 10.

Considering now the apparatus at point B, the current thus supplied to the rails of section B-C energizes both relays H^B and K^B in the reverse direction, and a circuit is then completed for lamp 65 of signal S^B over contact 45-45^b of relay H^B and contact 57-57^b of relay K^B. A primary circuit is closed for transformer T^B from the right-hand terminal of the secondary of transformer L^B, through contact 43-43^b of relay H^B, and primary 27 of transformer T^B to the mid-point of the secondary of transformer L^B. The secondary 26 of transformer T^B is connected with the rails of section A-B over contact 42-42^b of relay H^B, and contact 49-49^b of relay K^B. It should be observed that neither of the asymmetric units 38 or 39 is included in this secondary circuit so that full wave alternating current of normal relative phase

is now supplied to the rails of section A-B as shown in Fig. 11.

Current thus supplied to the rails of section A-B energizes relay H^A in the reverse direction and energizes relay K^A in the normal direction. A circuit is thus completed for lamp 66 of signal S^A over contact 45-45^a of relay H^A and contact 57-57^a of relay K^A. Primary 27 of transformer T^A is now connected with the right-hand portion of the secondary of transformer L^A, over contact 43-43^a of relay H^A. The secondary 26 of transformer T^A is connected, through contact 42-42^a of relay H^A and contact 49-49^a of relay K^A directly with the rails of the section to the left of point A so that the rails of this section are supplied with full-wave alternating current of normal relative phase.

It will be seen from the foregoing with the arrangement of apparatus shown in Figs. 1, 1^a and 1^b, I have provided a system of railway signaling in which nine separate and distinct indications are available without the necessity of providing line wires between locations.

It should be pointed out that although I have illustrated relays H and K as three-position, two-element relays, the functions of these parts could equally well be performed by two-position relays of the usual neutral type, the necessary modifications of the circuits being obvious from the inspection of the drawing, without further explanation.

Although I have herein shown and described only one form of electrical apparatus embodying my invention, it is understood that various changes and modifications may be made therein within the scope of the appended claims without departing from the spirit and scope of my invention.

Having thus described my invention, what I claim is:

1. In combination, two relays each having two windings and each being selectively responsive to the phase relation of currents in its windings, means for constantly supplying one winding of each relay with only half-waves of one polarity of alternating current of fixed-relative phase, means for supplying the remaining windings with only the positive or only the negative half-waves of alternating current of normal or reverse phase or with full-wave alternating current of normal or reverse phase or with only the positive or only the negative half-waves of alternating currents of both normal and reverse relative phase, and signaling means controlled by said relays.

2. In combination, a relay having two windings and selectively responsive to the phase relation of the currents in said windings, means for constantly supplying one winding with only half-waves of alternating current of one relative phase, means for supplying the remaining winding with only the

positive or only the negative half-waves of alternating current of such one relative phase or of another relative phase or with full-wave alternating current of such one or the other relative phase or with only the positive or only the negative half-waves of alternating currents of both said relative phases, other apparatus included in circuit with said remaining winding and responsive to alternating currents of said other relative phase, and signaling means controlled by said relay and by said other apparatus.

3. In combination, a stretch of railway track divided into sections, two relays for each section each having two windings and being selectively responsive to the phase relation of the currents in its windings, means for constantly supplying one winding of each relay with only half-waves of one polarity of alternating current of fixed relative phase, the second winding of each such relay being connected with the rails of the associated section, means controlled by the two relays for each section for supplying the rails of the section in rear with only the positive or only the negative half-waves of alternating current of normal or reverse phase or with full alternating current of normal or reverse phase or with only the positive or only the negative half-waves of alternating currents of both normal and reverse relative phase, and signaling means for each section controlled by said relays.

4. In combination, a stretch of railway track divided into sections, two relays for each section responsive to the relative phase and polarity of the currents in the rails of such section, means operating when the two relays of one section are both de-energized to supply the rails of the section next in rear with only the positive half-waves of alternating current of normal relative phase, means operating when the first relay for one section is de-energized for supplying the rails of the section next in rear with only the negative or only the positive half-waves of alternating current of reverse relative phase according as the second relay for said one section is energized in the normal or the reverse direction respectively, means operating when the first relay for one section is energized in the normal direction and the second relay for the section is de-energized to supply the rails of the section next in rear with full-wave alternating current of reverse relative phase, means operating when the first relay for a section is energized in the normal direction and the second relay for the section is energized in the reverse direction to supply the rails of the section next in rear with only the positive half-waves of alternating currents of both normal and reverse relative phases, means operating when the two relays for a section are both energized in the normal direction to supply the rails of the

section next in rear with only the negative half-waves of alternating current of normal phase, means operating when the first relay for a section is energized in the reverse direction and the second relay for the section is de-energized to supply the rails of the section next in rear with only the negative half-waves of alternating currents of both normal and reverse relative phase, means operating when the first relay for a section is energized in the reverse direction and the second relay for the section is energized in either the normal or reverse direction to supply the rails of the section next in rear with full-wave alternating current of normal relative phase, and signaling means for each section controlled by the associated relays.

5. In combination, a stretch of railway track divided into sections, two relays for each section selectively responsive to the phase and polarity of the current in the rails of the associated section, a track transformer for each section, means controlled by the two relays for a section for supplying the primary of the track transformer for the section next in rear with alternating current of normal or reverse relative phase, and means controlled by the two relays for each section for supplying only the positive or only the negative half-waves or full-wave alternating current from the secondary of the track transformer for the section next in rear to the rails of such section next in rear.

In testimony whereof I affix my signature.

HOWARD A. THOMPSON.
